UNITED STATES PATENT OFFICE

ARTHUR F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI

PULVERIZER

Refiling of abandoned application Serial No. 362,678, filed May 13, 1929. This application filed April 14, 1932. Serial No. 605,168.

My invention relates to new and useful improvements in pulverizers and more particularly to that class of machines known as the ring type in which the reduction of material is caused by a plurality of rings rotating within a pulverizing chamber. The rings are freely mounted and revolve on their axes.

Heretofore, it has been customary to mount the rings directly on the rotor disk. This caused several faults which restricted the use of the machines. If the machines were operated at other than relatively slow speeds, excessive vibration resulted, and to alter the fineness of the product it was necessary to make a major change in the machine, such as the substitution of different sized rings. Also, there is a tendency when the ring is mounted directly on the fixed shaft for the inner ring surface to become grooved so that all wear takes place against one portion of the outer face of said ring.

Having these faults in mind, the principal object of my invention is to provide a pulverizer in which the rings are mounted on a shaft movable in relation to the main shaft.

Another object of my invention is to provide means for adjusting the rings relatively to the grinding surface of the pulverizing chamber.

A further object is to restrict the size of the disks from which the rings are supported, thus making a more compact structure of the rotor.

With the foregoing and other objects in view, my invention consists in certain novel features of construction and arrangement of parts, hereinafter more fully described and claimed, and illustrated in the accompanying drawing, in which

Figure 1 is a vertical longitudinal section through my improved pulverizer illustrating the rings in extended position as when in operation.

Figure 2 is a vertical transverse section taken on line 2-2 of Figure 1.

Referring by numerals to the accompanying drawing, 1 indicates the base section of my improved pulverizer and includes all that portion of the machine below the medial

line. A shaft 2 is journaled at the upper edge of the base 1 and traverses this member. 3 is a cage which comprises a semi-cylindrical section fixed in the base 1 and arranged concentric with shaft 2. Cage 3 comprises preferably a plurality of transversely mounted bars 4 which may be of any desired shape and which are spaced according to the work to be done. The top 5 is suitably connected to base 1 so that it may be freely removed therefrom. Top 5 includes a feed spout 6 at the front portion of the machine.

Fixed to shaft 2 is a plurality of rotor disks 7 which are held in spaced apart relation by their hub portions 7a. Each disk 7 is provided with a plurality of apertures 8 arranged in groups, and the apertures of each group are disposed various distances away from the axis of shaft 2.

In the instant case there are four groups of apertures in each disk and when said disks are arranged on shaft 2 the apertures of each group of each disk are aligned with apertures of the corresponding groups of the other disks.

A rod or shaft 9 extends through a selected group of aligned apertures of said disks and is secured in position in said disks in any suitable manner.

A plurality of arms 10 are pivotally mounted at their inner ends on each rod 9 between each pair of spaced disks 2.

By placing the apertures 8 of each group at different radii relatively to the axis of rotation, shaft 9 and arms 10 carried thereby can be radially adjusted toward or away from shaft 2. The outer end of each arm 10 is provided with two or more openings 11 and 12 arranged longitudinally of the arm. The outer openings 11 of all of the arms of one group are in axial alignment with each other and the inner openings 12 are arranged likewise.

A horizontally disposed shaft or rod 14 passes through one set of openings, in the present instance the set numbered 11, and is secured in position in any suitable manner.

A plurality of rings 15 is arranged on each rod 14 and each ring is disposed between each pair of adjacent arms 10. Rings 15

15 have an enlarged central opening and are loosely mounted on rods 14 and each ring therefore has a certain amount of inward movement.

It will be noted that rings 15 may be adjusted radially with respect to the axis of rotation and toward or away from the cage 3 by shifting the positions of the outer rods 14 or by shifting the inner rods 9. The rotor disks 7 are of relatively small diameter, and 20 the machine is, therefore, capable of handling pieces of large size for reduction.

In the operation of my improved pulverizer, material to be reduced is fed through hopper or spout 6 into the pulverizing chamber where it is acted upon by the rapidly rotating rings 15. These rings are held in extended positions by centrifugal force, as illustrated in the drawing. Should an unusually large particle of material be fed into 25 the machine, it is possible for the rings, due to their flexible mounting, to yield and achieve the reduction of such large piece by a series of blows delivered by the following rings rather than forcing the reduction of the piece by the first rings. The rings are adjustable radially so that reduction of material of varying degrees of fineness can be had by spacing the rings toward or away 30 from the cage.

20 Due to the fact that the rings are loosely carried on rods 14 and the latter are pivotally mounted on the rotor disks 7, it is possible to operate my machine at a much higher speed than has heretofore been practicable 35 with machines of the ring type.

It is a well-known fact that the operation of such a machine at a high speed is a much more efficient method of operation because 40 power consumption is regular and there are no periodical strains on the mechanism which might cause undue wear and possible breakage.

This application is a substitute for an 45 application filed by me May 13, 1929, Serial No. 362,678.

It is to be understood that minor changes in the size, form and construction of the various parts of my improved pulverizer may be 50 made and substituted for those herein shown and described, without departing from the spirit thereof.

I claim:

1. In a pulverizer, a casing, and a rotor 55 mounted for operation within said casing, said rotor comprising a main shaft, a plurality of disks fixed to said main shaft, a radially adjustable shaft fixed in said disks, a plurality of pivotally connected arms 60 mounted on said disk shaft, a radially adjustable shaft carried by said arms, and a plurality of loosely mounted rings on said last mentioned shaft.

2. In a pulverizer, a casing, a rotor mount- 65 ed for operation within said casing, said

rotor comprising a main shaft, a plurality of disks fixed on said main shaft, a shaft mounted near the periphery of said disks and parallel to said main shaft, a plurality of pivotal arms on said disk shaft, a radially adjustable shaft mounted in and near the outer extremities of said arms, and a plurality of loosely connected rings mounted on 70 said last mentioned shaft.

3. In combination with a pulverizer, a 75 rotor having mounted thereon a pair of pivotally connected radial adjustable arms, a shaft mounted in the free ends of and connecting said pivotal arms, said shaft being radially adjustable relative to said rotor, 80 and a ring loosely mounted on said shaft.

4. In a pulverizer of the class described, the combination of a casing, a shaft journaled therein, a plurality of spaced-apart rotor disks fixed on said shaft, a plurality 85 of arms pivotally mounted on said disks, each arm being provided at its outer end with a plurality of apertures arranged at different radii from said shaft, said arms being arranged in a plurality of groups, the respective apertures of each group being axially aligned, a rod extending through one series of the aligned apertures of each group and carried by the arms of said groups, and a plurality of rings loosely mounted on each 90 rod between the outer ends of said arms.

5. In a pulverizer of the class described, the combination with a revoluble shaft and a plurality of spaced-apart disks fixed thereon, of a plurality of arms pivotally mounted 100 on said disks and extending radially outward from said shaft, each arm being provided at its outer end with a plurality of apertures arranged at varying radii relatively to said shaft, said arms being arranged in groups 105 and the respective apertures of each group being axially aligned, a rod extending through one series of apertures of each group and carried by said arms parallel with said shaft, and a plurality of rings loosely disposed 110 on each rod between the outer ends of said arms.

In testimony whereof I hereunto affix my signature this 5th day of April, 1932.

ARTHUR F. WILLIAMS. 115
